UNITED STATES PATENT OFFICE.

JAMES E. BULLOCK, OF NEW HAVEN, CONNECTICUT, ASSIGNOR TO THE GEOMETRIC TOOL CO., OF NEW HAVEN, CONNECTICUT, A CORPORATION.

DOUBLE-ENDED THREADING-DIE.

1,186,276.

Specification of Letters Patent. Patented June 6, 1916.

Application filed December 27, 1915. Serial No. 68,709.

To all whom it may concern:

Be it known that I, JAMES E. BULLOCK, a citizen of the United States, residing at New Haven, in the county of New Haven and State of Connecticut, have invented a new and useful Improvement in Double-Ended Threading-Dies; and I do hereby declare the following, when taken in connection with the accompanying drawings 10 and the characters of reference marked thereon, to be a full, clear, and exact description of the same, and which said drawings constitute part of this application, and represent, in—

15 Figure 1 a face view of a double-ended threading die or chaser constructed in accordance with my invention. Fig. 2 an edge view thereof. Fig. 3 an end view thereof. Fig. 4 an edge view of one of the modified forms which my improved threading-die or chaser may assume.

20 My invention relates to an improvement in threading-dies or chasers, the object being to produce a threading-die or chaser of superior convenience and economy, and designed with particular reference for use in the automatically opening die-heads of screw-cutting machines employed in the manufacture of screws and screw-machine products, as distinguished from threading dies or chasers designed for use in portable hand-operated threading-die stocks and kindred tools.

25 With these ends in view, my invention consists in a double-ended threading-die or chaser formed at its respective ends with cutting teeth located diametrically opposite each other, and also formed at its respective ends with transverse clearance-notches 30 located diametrically opposite each other, the said die being also formed in its respective faces with oppositely located longitudinal key-receiving grooves and in one of its edges with two retaining cam-receiving slots 35 placed on opposite sides of the transverse center of the die.

35 In carrying out my invention as herein shown, my improved double-ended threading-die or chaser is formed at its respective ends with cutting teeth 2 and 3 corresponding in pitch and in size as to fineness or coarseness, but located diametrically opposite each other with respect to the longitudinal axis of the die. I prefer to have the 45 teeth 2 and 3 alike, but that is not necessary.

The cutting faces 6 and 7 of the die are set inward adjacent to its longitudinal axis by the formation at the ends of the die of clearance-notches 4 and 5 also placed diametrically opposite each other. The respective 50 faces 8 and 9 of the die are formed with corresponding, oppositely located longitudinal key-receiving grooves 10 and 11 which receive the keys with which the die-head is provided for positioning the dies 55 therein. One edge of the die is also formed with two corresponding, inclined transverse cam-receiving slots 12 and 13 located on either side of the transverse center of the die and designed to receive the operating- 60 cams with which the die-heads are provided for holding the dies therein and operating them.

65 The modified form of die 14 shown in Fig. 4, corresponds to the die of Figs. 1, 2 and 3 in every respect except that the cutting-teeth 15 and 16 at its respective ends, are curved instead of straight, these teeth being conformed in curvature to the curvature of the object which they are designed to thread. 70

75 Under the specific construction above described, I secure superior convenience, since the die, when worn at one end, may be readily reversed and the other end used. Then both ends of the die may have their cutting 80 teeth reground with less outlay of time and labor than would be required to regrind the cutting edges of separate dies. Furthermore, by my invention, I secure a great 85 economy, since without materially adding to the amount of "high speed" steel in one die, 90 I virtually convert it into two dies.

95 By locating the cam-receiving slots in the same edge of the die on opposite sides of its transverse center, I secure all of the advantages of a reversible die or chaser without impairing its strength, since the transverse sectional area of the die is not reduced by a plurality of cam-receiving slots as long as they are all located in one of its edges 100 whereas when the slots are located in both of its edges, the strength of the die is materially impaired.

105 I am aware that a double-ended threading-die is not broadly new, and claim only my particular construction.

I claim:—

110 A double-ended threading-die or chaser for use in the automatically opening die-heads of screw-cutting machines, the said die

being characterized by having its respective ends formed with cutting-teeth, and further characterized by having two corresponding cam-receiving slots respectively located at 5 equal distances from its cutting teeth and formed in one and the same edge of the die for the reception of the cam in the die-

head, whereby the chaser is made reversible end for end in an automatically opening die-head provided with a cam arranged for 10 coöperation with a non-reversible die or chaser having a cam-slot located in one of its ends.

J. E. BULLOCK.
